UNITED STATES PATENT OFFICE

JAMES M. NAUL, OF PLAINFIELD, NEW JERSEY, ASSIGNOR TO THE SINGER MANUFACTURING COMPANY, OF ELIZABETH, NEW JERSEY, A CORPORATION OF NEW JERSEY

ELECTRIC SEWING MACHINE

Application filed July 12, 1928. Serial No. 292,168.

This invention relates to electric sewing machines and has for an object to provide an improved and simplified mechanism for driving and controlling the speed of such machines.

The invention consists in the devices, combinations and relative arrangements of parts hereinafter described and claimed.

In electric sewing machine outfits it has been customary, up to the present time, to mount the electric motor on the sewing machine gooseneck and connect it by suitable wiring to a motor-controller variously situated in outfits of various types. For example, in the portable type of sewing machine outfit the controller has been mounted in the hollow wooden base of the carrying case. In the drop-head cabinet or library table outfit, the controller has been located below the table-top and within the side walls or skirt-members of the table. With other outfits, foot-operated controllers have been employed; such controllers being placed upon the floor for use and stored in the machine cabinet or carrying case when not in use. These various dispositions of the motor-controller make it necessary for the manufacturer to provide connecting leads of various lengths together with a variety of fittings and accessories for wiring up the variously situated controllers.

With the idea of standardizing and simplifying the electrification of the various types of sewing machines, there is provided, in accordance with the present improvement, a unitary assembly of motor and motor-controller, with the necessary wiring, standardized in one form, which assembly is complete in itself, apart from the sewing machine, and is adapted for attachment to or removal from the sewing machine by one not possessed of mechanical or electrical skill.

To avoid the necessity of shifting the motor into or out of operative position when the machine is to be used or put away, advantage is preferably taken of the flat motor disclosed in the U. S. patent to Diehl et al. No. 1,488,234, of March 25, 1924. There is combined with this motor, a motor-control-

ler or rheostat, preferably of the compression type, which is mounted on the motor between the planes of the flat sides of the motor field-frame. The rheostat may be conveniently mounted on the motor by providing the motor end-bonnets with upward extensions forming controller-seats to which the controller is secured. Projecting forwardly from the motor is the manual means for operating the controller; such means being preferably in the form of a knee-lever supporting rock-shaft journaled in the motor-supporting bracket and carrying an arm arranged to operate the controller. The bracket carrying the complete assembly may be secured to the usual driving attachment seat, commonly provided on the sewing machine gooseneck, by the application of a single screw.

The several features of the invention and the advantages attained thereby will be readily understood by those skilled in the art from the following description taken in connection with the accompanying drawings which illustrate the several features of the invention as embodied in a portable electric sewing machine.

In the accompanying drawings, Fig. 1 is a front elevation of an electric sewing machine embodying the invention. Fig. 2 is a rear end elevation of the machine. Fig. 3 is a perspective view of the electric motor. Fig. 4 is a horizontal section through the standard of the sewing machine gooseneck, showing the motor and motor-controller in plan. Fig. 5 is a longitudinal vertical section through the motor and motor-controller. Fig. 6 is a transverse vertical section through the same, and Fig. 7 is a perspective view of the supporting bracket for the parts of the electrification assembly.

For the purposes of the present disclosure, the invention is shown as embodied in a sewing machine of the portable type. Such a sewing machine comprises the usual bed 1, from which rises the standard 2 of the gooseneck 3 carrying the usual reciprocating needle 4, presser-foot 5 and balance-wheel 6. The bed 1 rests upon the wooden base-section 7 of the carrying case, including the

cover-section 8; the base 7 being shown as stationed for use upon an ordinary table 9.

The standard 2 is formed near the bed 1 with the usual driving-attachment seat 10 including the vertical rib 11 to which is secured by the screw 12 the vertically slotted seat 13' of the bracket 13, Fig. 7, having a rearwardly extending arm 14 terminating in an inclined portion 15 to which is secured by the screw 16 the combined flat motor and controller 17.

The motor comprises the usual laminated field-frame 18 clamped between the end-bonnets 19 having bearings 20, Fig. 5, for the motor-shaft 21 to which is fixed the belt-pulley 22 connected by the belt 23 to the balance wheel 6. The field-frame is flattened at opposite sides 24, 24 and is permanently situated in the space between the standard 2 and the rear wall of the housing or cover 8.

The end-bonnets 19 are formed with seats 25 and upstanding flanges 26, 27, upon which seats and between which flanges is fixed the controller 28 in the form of a compression rheostat having substantially the constructive features of the rheostat disclosed in the U. S. patent to Chason, No. 1,643,292, of September 27, 1927. Such a rheostat comprises a porcelain body formed with a pair of wells filled with stacks of carbon disks 29 at the ends of which stacks are the terminal members 30, 31. The terminal members 30 are connected to metal strips 32 carrying the terminal binding screws 33. The terminal members 31 are connected and have a variable pressure exerted thereon by the weak bow-spring bridging contact-member 34 backed by the somewhat stiffer spring 35, both carried by the endwise movable rod 36 parallel to the motor-shaft 21 and surrounded by the relatively strong recovery spring 37. Fixed to the inner end of the rod 36 is a guide-head 38 working in a slot 39 in the porcelain body 28. At the inner extreme of the motion of the rod 36, the guide-head presses the rheostat short-circuiting spring 40, secured to one of the terminals 30, into engagement with the contact-plate 41 secured to the other terminal 30. The push-button 42 mounted in the flange 19 in axial alinement and contact with the rod 36 is adapted to move the latter in opposition to the spring 37.

The rheostat and motor are connected in series relation to the two-pin terminal plug 43 mounted on the bracket 14 and adapted to receive a mating plug-member connected to the current-supply cord (not shown).

Journaled in the forwardly extending arm 44 of the bracket 13 is a rock-shaft 45 to which is fixed the upstanding arm 46 having at its upper end the rearward ex- 65 tension 47 paralleling the flange 26 and

transverse to the motor-shaft 21 and engaging the pushbutton 42 which lies and moves parallel to the motor-shaft 21.

The rock-shaft 45 supports the manually operated knee-lever 48 which is detachably connected to the rock-shaft 45 by a form of bayonet joint including the socket element 49 formed with a tooth 50 adapted to be slipped onto the end of the rock-shaft 45 and turned to engage the tooth 50 with the tooth 51 on the collar 52 fixed to the rock-shaft.

The motor-frame is formed externally with an inclined rib 53 which fits in the groove 54 extending longitudinally of the inclined portion 15 of the bracket 14. By removing the screw 16, the motor and rheostat may be adjusted outwardly along the inclined arm to a position where the screw-hole 55 in the motor-frame registers with the screw-hole 56 in the arm 15; the screw 16 being inserted in the registering screw-holes to secure the motor and controller in the new position of adjustment shown in dotted lines in Fig. 2. This adjustment may be made to adapt the motor assembly to a sewing machine having a somewhat thicker gooseneck than that shown in the drawing. The direction of inclimation of the arm 15 is such that the belt length is not altered by the adjustment; the construction being substantially in accordance with the disclosure of U. S. patent to Hemleb, No. 1,520,949, of December 30, 1924. It will be noted that the push-button 42 in the new position of adjustment is not carried out of engagement with the arm 47.

The disposition of the rheostat on the motor frame frees the cavity 57 in the wooden base which formerly housed it, for its originally intended use as a receptacle for the usual sewing machine attachments. The cavity 57 is closed by a removable cover 58.

While the invention is disclosed as embodied in a sewing machine of the portable type having a flat motor, it is to be understood that the invention is not limited to any particular type of sewing machine, nor is it limited, except as defined in certain of the claims, to the use of a flat motor.

Having thus set forth the nature of the invention, what I claim herein is:

1. A bracket, motor and motor-controller elements mounted on said bracket, a rock-shaft carried by said bracket independently of said motor and motor-controller elements and connected to operate said motor-controller element, and manually controlled means for operating said rock-shaft.

2. An electric driving device for sewing machines comprising a bracket having forwardly and rearwardly extending arms, a motor and motor-controller mounted on the rearwardly extending arm of said bracket,

a rock-shaft journaled in the forwardly extending arm of said bracket and connected to operate said motor-controller, and manually controlled means for operating said 5 rock-shaft.

3. The combination with a bracket, of a combined electric motor and motor-controller unit mounted on said bracket, means permitting adjustment of said unit relative 10 to said bracket in a direction transverse to the motor-shaft, said motor-controller having an operating push-button parallel to the motor-shaft, and a manually operated lever-arm mounted on said bracket and including a portion disposed in a plane transverse to the motor-shaft and adapted to engage said push-button in different positions 15 of adjustment of said unit.

4. The combination with an electric motor 20 having a frame and shaft, of a rheostat mounted on said motor-frame and including an endwise movable resistance controlling rod disposed substantially parallel to the motor-shaft, a bracket carrying said motor, 25 a manually controlled rock-shaft journaled in said bracket transversely of the motor-shaft, and an arm carried by said rock-shaft and adapted to engage said resistance controlling rod.

5. In an electric driving device for sewing machines, in combination, a bracket, an electric motor mounted on said bracket and having a shaft, a motor-controller mounted on top of said motor, and a rock-shaft journaled in said bracket transversely of the 35 motor-shaft and connected to operate said controller.

6. A sewing machine driving device comprising a motor having a pair of end-bonnets, a laminated field-frame clamped between said end-bonnets, an armature having a shaft journaled in said end-bonnets, said end-bonnets being each formed with a controller seat, and a motor-controller secured 45 to said seats and bridging the space between said end-bonnets.

7. A sewing machine driving device comprising a motor having a pair of end-bonnets, a laminated field-frame clamped between said end-bonnets, an armature having a shaft journaled in said end-bonnets, said end-bonnets being each formed with a controller seat and an end-flange extending beyond said seat, and a motor-controller secured 55 to said seats and disposed between said end-flanges.

8. A sewing machine driving device comprising a motor having a pair of end-bonnets, a laminated field-frame clamped between said end-bonnets, an armature having a shaft journaled in said end-bonnets, said end-bonnets being each formed with a controller seat and an end-flange extending beyond said seat, and a motor-controller secured 65 to said seats and disposed between

said end-flanges, said motor-controller including an endwise movable operating rod disposed substantially parallel to the motor-shaft and passing through one of said end-flanges.

9. A bracket having a side attaching seat and an arm extending rearwardly from said seat, motor and rheostat elements mounted on said rearwardly extending arm at the same side of said arm as said seat, a terminal plug member mounted on the opposite side of said arm, and manually operated means carried by said bracket and arranged to operate said rheostat element.

In testimony whereof, I have signed my 80 name to this specification.

JAMES M. NAUL.
